UNITED STATES PATENT OFFICE.

WILLIAM R. RAY, OF SAN FRANCISCO, CALIFORNIA.

BURNER-MOUNTING.

1,328,198.

Specification of Letters Patent.

Patented Jan. 13, 1920.

Application filed July 31, 1919. Serial No. 314,577.

To all whom it may concern:

Be it known that I, WILLIAM R. RAY, a citizen of the United States, residing in the city and county of San Francisco and State 5 of California, have invented new and useful Improvement in Burner-Mountings, of which the following is a specification.

This invention relates to a burner mounting and especially to a mounting for oil 10 burners of the centrifugal atomizing type.

One of the objects of the present invention is to provide a simple and substantial motor driven crude oil burner of the rotary type in which the oil is ejected and atomized by 15 the combined action of centrifugal force and an air blast, and particularly to provide means for protecting the burner against radiant and conducted heat of the furnace.

Another object of the invention is to provide 20 a novel mounting for the burner to permit it to be readily moved to or away from the furnace opening and also to provide a substantial support for a refractory lining by which the burner is protected, said 25 support being also movable to permit renewal of the lining or cooling of the same.

Further objects will hereinafter appear.

The invention consists of the parts and the construction, combination and arrangement of parts as hereinafter more fully described and claimed, having reference to the 30 accompanying drawings, in which—

Figure 1 is a perspective view of a furnace front, showing the application of the 35 invention.

Fig. 2 is a front view of the same.

Fig. 3 is a perspective view of the refractory brick or tile support.

Referring to the drawings in detail, A 40 indicates a rectangular-shaped plate which is constructed so that it may be readily attached to a furnace front and the like by means of bolts 2. Formed around the outer edge of the plate A are flanges 3, 4, 5 and 6, 45 these flanges being provided for the purpose of supporting the plate A if it is desired to build it right into the brick work of the furnace front. Formed on the outer flange 6 are a pair of supporting lugs 7 and passing 50 through said lugs is a pipe 8 which serves as a pintle for the burner generally indicated at B, a nozzle supporting door 9 and a tile supporting door 10. The respective doors 9 and 10 are supported by means of a 55 pintle or pipe 8 as hinge lugs 11 and 12 are

formed on the respective doors, the burner being in this instance supported in a similar manner as hinge lugs 13 are formed on the fan casing, as will hereinafter be described. The door 10 consists of a plate around which 60 is formed channel-shaped flanges (see Fig. 3), as indicated at 14, 15 and 16. Adapted to be supported by said flanges is a tile plate 16^A in which is formed a central opening 17. The tile may be constructed of any suitable 65 refractory material or a series of bricks may be placed therein.

The hinges 11, by which the door 10 is supported, permit it to be swung outwardly with relation to the furnace plate and it is 70 therefore possible to remove the tile 16^A or the bricks contained therein, whenever desired, without destroying the burner mounting or any of the connections formed therewith. The door 9 is also free to swing about 75 the pintle and it is provided in this instance as a support for a nozzle 18, said nozzle being so arranged that it will project through the opening 17 formed in the tile. The oil burner proper indicated at B consists of an 80 electric motor 19, which is supported by a central bearing member 20 and a fan housing 21, said fan housing being supported on the pintle 8 by means of the hinge lugs 13. Formed on the inner face of the fan 85 housing is a nozzle 22 and mounted interior of said nozzle is a centrifugal atomizer to which oil is delivered by means of a pipe 23, said pipe extending through the motor shaft as this is hollow. The oil is otherwise 90 delivered to the pintle 8 as this is hollow and it is conveyed from the pintle to the pipe 23 by means of the pipes indicated at 24 and 25, the flow of oil being regulated by means of a valve 26. 95

In actual operation, with a centrifugal burner mounted as here shown, it can readily be seen that the burner may be swung to or from the furnace opening as the whole unit is supported on the pintle 8 by means of the 100 hinge lugs 13 and that said movement may take place without disturbing any of the oil delivering connections as the oil is delivered by means of a hollow pintle 8. The doors 9 and 10 are closed when the burner is in 105 operation and the burner is furthermore swung directly up against the door 9 when in operation, to permit the atomized oil and air discharging through the nozzle 22, to pass through the nozzle 18 and the opening 110

17 formed in the tile plate 16. The atomized fuel and air will then enter the furnace where combustion takes place.

By referring to Fig. 1, it will be seen that lugs 27 are formed on the forward face of the door 9. These lugs serve the function of maintaining a space between the fan casing and the door, thereby permitting air to enter between the nozzles 22 and 18; that is, the atomized oil and air discharging through nozzle 22 produces a jet action in the nozzle 18, thereby inducing a secondary flow of air between the fan casing in the door 9 which enters an annular passage formed between the nozzles 18 and 22. This is of great importance as it not only supplies an ample quantity of air to the furnace chamber but it also serves the function of cooling the burner proper, thereby preventing overheating of the nozzle 22 or burning out of the bearings containing the fan and motor. Overheating of these parts is further taken care of as the tile plate 16 shields the burner proper, both against radiant and conducted heat.

The fan casing may be locked with relation to the door 9 by means of a swivel catch 30. The door and the fan casing may therefore be opened or closed in unison or independently of each other. The door 10 is normally maintained in a closed condition by means of a swivel latch 31 as it is not necessary to open the door 10 except when it is desired to rapidly cool the furnace or to renew the tiles 16 or the brick lining contained therein.

From the foregoing description it should be obvious that a simple, substantial and desirable mounting has been provided for an oil burner of the type here shown. First, because it is possible to protect the burner against radiant and conducted heat of the furnace by means of the refractory lining provided. Secondly, it becomes possible to induce a secondary supply of air which not only assists combustion within the furnace but further, serves the function of cooling the burner. Third, it is possible to swing the burner away from the furnace opening or to swing any of the doors shown, about the pintle without disturbing the connections by which the oil is delivered.

Having thus described my invention, what I claim and desire to secure by Letters Patent is—

1. A burner mounting comprising a furnace front plate, a door hingedly secured to said plate having a central opening formed therein, a burner also supported on the same hinge mounting adapted to be swung to or from the central opening in the door, and means on the interior side of the door for supporting a refractory lining.

2. A burner mounting comprising a furnace front plate, a door hingedly secured to

said plate having a central opening formed therein, a burner also supported on the same hinge mounting adapted to be swung to or from the central opening in the door, a channel-shaped flange formed on the inner side of the door and a refractory lining supported in said flange. 70

3. A burner mounting comprising a furnace front plate, a door hingedly secured to said plate having a central opening formed 75 therein, a burner also supported on the same hinge mounting adapted to be swung to or from the central opening in the door, a channel-shaped flange formed on the inner side of the door, on the sides and on the 80 bottom, and a refractory tile member supported by and removable with relation to said channel-shaped flanges.

4. A burner mounting comprising a furnace front plate, a pair of supporting lugs 85 formed on one side of said plate, a hollow pintle member extending through and secured in said lugs, a door hingedly mounted on said pintle having a central opening formed therein, a burner also supported on 90 the pintle and adapted to be swung to or away from the opening in the door, a channel-shaped flange formed on the sides and on the bottom of the door and on the inner side thereof, and a refractory tile member 95 supported by and removable with relation to said channel-shaped flanges.

5. A burner mounting comprising a furnace front plate, a pair of supporting lugs formed on one side of said plate, a hollow 100 pintle member extending through and secured in said lugs, a door hingedly mounted on said pintle having a central opening formed therein, a burner also supported on the pintle and adapted to be swung to or 105 away from the opening in the door, a channel-shaped flange formed on the sides and on the bottom of the door and on the inner side thereof, a refractory tile member supported by and removable with relation to 110 said channel-shaped flanges, a second door hingedly mounted on a pintle member, said door being interposed between the first named door and the burner, a nozzle member on said door projecting through the 115 central opening in the first named door, means for maintaining a spacing between the burner and the second named door, and means for securing the burner with relation to the second named door. 120

6. A burner mounting comprising a furnace front plate, a pair of supporting lugs formed on one side of said plate, a hollow pintle member extending through and secured in said lugs, a door hingedly mounted 125 on said pintle having a central opening formed therein, a burner also supported on the pintle and adapted to be swung to or away from the opening in the door, a channel-shaped flange formed on the sides and 130

on the bottom of the door and on the inner side thereof, a refractory tile member supported by and removable with relation to said channel-shaped flanges, a second door 5 hingedly mounted on a pintle member, said door being interposed between the first named door and the burner, a nozzle member on said door projecting through the central opening in the first named door, means 10 for maintaining a spacing between the burner and the second named door, means for securing the burner with relation to the second named door, and a nozzle on the burner projecting into the nozzle formed on 15 the second named door, said nozzle burner being of smaller diameter than the first named nozzle to form an annular air admitting passage between the two nozzles.

7. A burner mounting comprising a furnace front plate, a pair of supporting lugs formed on one side of said plate, a hollow pintle member extending through and secured in said lugs, a door hingedly mounted 20 on said pintle having a central opening formed therein, a burner also supported on the pintle and adapted to be swung to or away from the opening in the door, a channel-shaped flange formed on the sides and

on the bottom of the door and on the inner side thereof, a refractory tile member supported by and removable with relation to said channel-shaped flanges, a second door 30 hingedly mounted on a pintle member, said door being interposed between the first named door and the burner, a nozzle member on said door projecting through the central opening in the first named door, means for maintaining a spacing between the burner and the second named door, means for securing the burner with relation 35 to the second named door, a nozzle on the burner projecting into the nozzle formed on the second named door, said nozzle burner being of smaller diameter than the first named nozzle to form an annular air admitting passage between the two nozzles, 40 and an oil delivering connection formed between the pintle and the burner.

In testimony whereof I have hereunto set my hand in the presence of two subscribing 45 witnesses.

WILLIAM R. RAY.
